UNITED STATES PATENT OFFICE.

CHARLES F. ROPER, OF HOPEDALE, MASSACHUSETTS, ASSIGNOR TO THE DRAPER COMPANY, OF PORTLAND, MAINE.

APPARATUS FOR MAKING CRANK-SHAFTS.

SPECIFICATION forming part of Letters Patent No. 604,267, dated May 17, 1898.

Application filed September 27, 1897. Serial No. 653,088. (No model.)

To all whom it may concern:

Be it known that I, CHARLES F. ROPER, of Hopedale, county of Worcester, State of Massachusetts, have invented an Improvement in

5 Apparatus for Making Crank-Shafts, of which the following description, in connection with the accompanying drawings, is a specification, like letters and figures on the drawings representing like parts.

10 This invention has for its object the production of an improved apparatus for making metal crank-shafts wherein the crank-arms are integral with the shaft, such shafts being particularly adapted for use in looms and 15 other apparatus wherein a large and heavy shaft is not required.

In practicing my invention the shaft is made from a preferably cylindrical rod or blank, which is heated and given a preliminary bend 20 at the point where the crank is to be made. Suitable dies then act upon the preliminary bend, reversing its curvature and forming the sides and end of the crank, while a third step 25 serves to set up the crank and finish it, at the same time bringing it into proper relation with the main portion of the shaft.

Figure 1, in partial side elevation and broken out to save space, represents an apparatus embodying my invention. Fig. 2 is a 30 partial left-hand end elevation thereof, the die and "former" being shown as separated. Fig. 3 is an under side view of the die to more clearly show the construction thereof. Fig. 4 is a vertical longitudinal sectional view of the apparatus on the line xx , Fig. 5. Fig. 5 is a top or plan view of the apparatus shown 35 in Fig. 1 with the die omitted. Fig. 6 is an elevation of the blank. Figs. 7, 8, and 9 are detail views showing the successive forms 40 through which the crank passes in the process. Fig. 10 is a top view of the finished crank; and Fig. 11 is a transverse sectional detail taken on the line $x'x'$, Fig. 9, looking down.

Referring to Figs. 1, 2, 4, and 5, the apparatus 45 comprises a suitable base or stand A, having uprights A', provided with guides A $\times$, on which a cross-head B is adapted to be vertically reciprocated by any suitable mechanism. (Not shown and forming no part of my 50 invention.) The cross-head is undercut on

its lower face, as best shown in Fig. 2, to receive a die D, which coöperates with a fixed or stationery former F, suitably held in the top of the base below the die. The former has at one side two upwardly and oppositely inclined faces f, provided with longitudinal grooves or seats f', with a blunt wedge-shaped depression between them, formed by the flat converging walls f $\ddot{a}$, preferably at right angles to the seats, the bottom of the depression 60 having a recess or seat f $\times$ formed therein.

As shown in Fig. 5, the seats f' f $\times$ are in alinement, and they serve to hold the blank and partially shape the crank by the coöperation of the die D, which latter is provided on 65 its face with a projection d, having flat downwardly-converging sides d' and a recess d $\ddot{a}$ in its lower end, the projection d corresponding in general shape with the depression between the faces f of the former.

70 A heavy block 5 of metal is rigidly secured to the former above and adjacent one of the seats f' to act as an abutment for the end of the blank b $\times$, Fig. 6, the blank being of suitable length and of the diameter desired for 75 the crank-shaft to be made therefrom.

As best shown in Figs. 1 and 4, a bracket c at the rear end of the former supports a plunger c', longitudinally movable in the adjacent seat f', said plunger having its reduced shank 80 c $\ddot{a}$ extended through the bracket and surrounded by a strong spring s to normally maintain the plunger pushed upward, as in Fig. 1. The plunger acts as a yielding stoppage for the end of the blank, determining 85 the distance of the crank from the end of the shaft, and it gives slightly when the preliminary bend is made in the blank, as will be described.

At back and front of the projection d on 90 the die are located extensions d $\ddot{a}$, having inclined faces d $\ddot{a}$, provided with longitudinal depressions or seats d $\ddot{b}$, which coöperate with the faces f and seats f', respectively, of the former, the opposing pairs of seats just receiving and tightly holding parts of the blank 95 when the die has fully descended, as in Fig. 1.

The blank b $\times$ is first heated in a suitable furnace, and then one end is placed in the rear seat f' of the former beneath the abut- 100

ment 5 and against the stop c' , after which the workman bends the blank over and down into or toward the front seat f' , giving the preliminary bend b^{20} . (See dotted lines, Fig. 1.)

5 The cross-head and die D then descend, and the grooved end d^2 of the projection d engages the blank at about the middle of the preliminary bend, reversing the curvature of the latter as the die descends to position 10 shown in Fig. 1. The crank-arms C, Fig. 7, are flattened somewhat between the faces d^2 , while the connecting-bar C^X is shaped by the recesses $d^2 f^X$, the arms C being at right angles to adjacent portions of the blank, as 15 clearly shown in Fig. 7, but inclined toward each other. As the die closes upon the former there is some tendency of the blank to elongate in the seats f' , and at the rear end the yielding gage c' accommodates itself to the 20 elongation. After the crank is thus partially made the next step is to straighten up and set the crank, with the two parts of the shaft in alinement, and this is effected by removing the blank from the seats f' and inserting 25 the end b^2 in a longitudinal groove h in the former beneath a holding-block 8, Figs. 4 and 5, and bringing the crank over the upturned projection h^X of the former. The blank bends readily at the points 23, Fig. 7, and the crank 30 is made to straddle the projection h^X , with the cross-bar C^X resting in the depression h' in the top of the projection, an arm C at each vertical end of the latter, and the longer part 35 b^3 of the blank is positioned in the depression h^2 in alinement with the depression h . The blank is then ready to be acted upon by a second descent of the die D to set the crank, the die having a recess d^7 therein (see dotted lines, Figs. 2 and 4) to receive the projection h^X , said recess having a depression d^8 40 therein, semicircular in cross-section, to receive one-half of the connecting-bar C^X . In alinement with each other and with the depression d^8 are two longitudinal depressions 45 $d^9 d^{10}$ in the face of the former F to receive, respectively, the parts $b^2 b^3$ of the blank. The closure of the die upon the former acts to fix or accurately set the crank, with its arms C, in parallelism and at right angles to the 50 shaft and the connecting-bar C^X of the crank, and at the same time to shorten the arms C, spreading them slightly in a lateral direction. In Fig. 8 the blank is shown with the crank-arms substantially in parallelism and at right 55 angles to the shaft, while in Fig. 9 is shown the crank after it has been set as just described, it being noticed that the arms C of the crank have been shortened. The flattened outer faces of the crank-arms are shown 60 most clearly in Fig. 10. Finally, if desired, the crank may be swaged to give the reduced arms the substantially elliptical shape shown in Fig. 11, this swaging being done by turning the crank on its side on the former in the 65 swaging-recess S, a corresponding recess S' being formed in the face of the die. Thus by slight manual manipulation in connection

with three operations of the die and former a complete crank is formed in the blank integral with the material of the shaft and accurately positioned with relation thereto, the final step of swaging insuring the absolute truing of the crank with relation to the shaft. 70

In looms and some other apparatus it is usual to provide the crank-shaft with two cranks, one near each end, and I have provided means in connection with my apparatus for effecting the true alinement of one crank with the other. 75

Referring to Figs. 4 and 5, trunnion-plates 80 g are rigidly secured to each side of the former and recessed at their upper ends at g' to receive the trunnions g^X of two lever-arms G, preferably having counterweights W at their rear ends, said levers being connected at one 85 end by a bolt g^2 and at the forward ends by a cross-bar. This cross-bar has a forward extension G^2 , and toggle-links $g^3 g^4$, pivotally connected together at g^5 , are jointed at g^6 and g^7 to the extension G^2 and the base A of the 90 apparatus, respectively, as clearly shown in Fig. 4, the toggle when strained bringing the extensions G^3 into substantially horizontal position. At its outer end said extension-arm supports a block M, adjustably secured in 95 place by suitable bolts m^X , the block having formed therein a substantially U-shaped recess m in the vertical plane of the seats f' of the former, a groove m' in the top of the block at each side of the recess m being also in 100 alinement with the said seats.

Supposing now that one crank has been formed, as described, the other end of the blank is heated and its end inserted beneath the abutment 5 and against the stop-gage c' , 105 after which the preliminary bend is made in the blank, as before described, and the crank is partially formed, the completed crank being inserted in the recess m of the guide-block M, at such time the extension G^2 being substantially horizontal, as shown in Fig. 4. The toggle is then broken and the lever-arms G are swung on their trunnions into the position shown in Fig. 1, thus completing the bend, the parts of the shaft adjacent the completed crank resting in the grooves m' of the guide-block. The recess m is of such a shape and size as to permit no lateral play of the completed crank; but, as shown in Fig. 1 by dotted lines, it is somewhat longer than the 110 distance between the outer faces of the crank-arms C. This is to allow for slight movement of the shaft as the preliminary bend is made, and it will be understood that the stop-gage c' is of such a length as will give the proper 115 length to the outer end of the shaft beyond the crank. While the parts are in the position shown in Fig. 1 the die D descends to reverse the curvature of the preliminary bend and form the second crank in the shape shown 120 in Fig. 7. The die then ascends and the attendant lifts the shaft out from both the former and the guide-block M, and, turning the shaft around, inserts the short end 125

nearest the second crank beneath the holding-block 8 on the former and proceeds to straighten up the second crank, as before described. The second crank having thus been brought in position over the projection h^x of the former, the die descends and sets the crank; but before the descent of the die the completed crank has been made to straddle a guide projection n on the guide-block, the said projection having in its top a grooved seat n' for the connecting-bar C^x of the completed crank, the adjacent portions of the shaft resting in grooves $n^2 n^3$ at the front and back of the guide projection n and in alignment with the longitudinal grooves $h h^2$ in the former and in the same horizontal plane. The completed crank being thus held in position, it is impossible for the second crank to be set out of true as the die D descends for the second time. Thus during the first forming action of the die and former and during the second action the second crank in process of formation is positively maintained in proper position relative to the finished crank and the shaft.

A brace g^{10} may be employed to connect the guide-block M with the longer portion of the cross-bar G' to steady the guide-block, the brace depending through a depending ear m^{10} on the said block.

By the apparatus hereinbefore described crank-shafts may be made very rapidly and accurately, the cranks forming integral portions of the shaft, and it will be obvious that double or single crank-shafts may be made with my apparatus.

By adjusting the guide-block M on the extension G^2 the distance between the two cranks is regulated.

Having fully described my invention, what I claim, and desire to secure by Letters Patent, is—

1. In an apparatus of the class described, a "former" having upwardly and oppositely inclined seats for and to receive the portions of the blank, at each side of and adjacent a preliminary bend therein, and a depressed portion between the inner ends of the seats, and a retaining device for one end of the blank when preliminarily bent to rest in said seats, combined with a coöperating die adapted to engage the convex side of the preliminary bend in the blank between the seats and reverse the curvature thereof, the die forcing the bent portion of the blank into the depressed portion of the "former," to thereby make the bottom and sides of the final bend or crank, substantially as described.

2. In an apparatus of the class described, a "former" having upwardly and oppositely inclined seats for the preliminarily - bent blank, and a wedge-shaped depression between them, the converging sides of said depression being substantially at right angles

to the adjacent seats, combined with a co-
operating die having a wedge-shaped projec-
tion to engage the bent portion of a blank
resting in the seats and to force the same into
the depression of the "former," substantially
as described.

3. In an apparatus of the class described,
a "former" having upwardly and oppositely
inclined seats and a wedge-shaped depression
therebetween; a projection on the former hav-
ing a recessed top, and longitudinal seats in
the "former" oppositely extended from the
base of said projection, in alinement with each
other and in the plane of the recess; and a
swaging-recess in said "former," combined
with a die having a wedge-shaped projection
to coöperate with the similarly - shaped de-
pression in the "former;" a cavity in the die
to be entered by the projection on the "form-
er," and a swaging-recess, whereby a blank
may be acted upon by said die and "former"
to form successively a bend therein having
divergent sides, straighten the sides of and
set the bend, and finally swage the latter,
substantially as described.

4. In an apparatus of the class described,
a "former," a coöperating die, one of which
is movable toward and from the other, said
die and "former" being constructed to act
upon a blank to form a crank therein by suc-
cessive steps, and a yielding stop-gage for
the end of the blank, substantially as de-
scribed.

5. In an apparatus of the class described,
a "former," a coöperating die, one of which
is movable toward and from the other, said
die and "former" being constructed to act
upon a blank to form a crank therein by suc-
cessive steps, a guide-block to receive a com-
pleted crank while a second crank is being
formed in the blank, and a pivotally-mounted
support for said guide-block, substantially as
described.

6. In an apparatus of the class described,
a "former," a coöperating die, one of which
is movable toward and from the other, said
die and "former" being constructed to act
upon a blank to form a crank therein by suc-
cessive steps, a guide-block having a crank-
receiving recess, a projection to hold the com-
pleted crank when the blank is reversed, and
means to move the guide-block, said recess
and projection thereon being adapted to co-
operate respectively with successively-oper-
ating portions of the die and "former," sub-
stantially as described.

In testimony whereof I have signed my
name to this specification in the presence of
two subscribing witnesses.

CHARLES F. ROPER.
